UNITED STATES PATENT OFFICE

HERMAN R. KUEHNER, OF LAUREL SPRINGS, NEW JERSEY

UMBRELLA HOLDER

Application filed February 24, 1930. Serial No. 430,840.

My invention relates to new and useful improvements in an umbrella holder, and has for one of its objects to provide an exceedingly simple and effective device of this character which is particularly adapted for use as a household article and which may be used as a stand or base for a standard, the latter being utilized as a means of transporting the umbrella holder or for supporting articles.

10 Another object of the invention is to produce an umbrella holder including a receptacle having a chambered pedestal therein, the chambers adapted to receive the tips of umbrellas and said chambers being in communication with the receptacle whereby drip water from the umbrella entering any of the chambers will flow into the receptacle.

Another object of the invention is to so construct the chambered pedestal that the lower ends of the chambers will be elevated relative to the bottom of the receptacle in order that the drip water entering said chambers will flow out into the receptacle.

20 A further object of the invention is to provide an umbrella holder including a receptacle having a wide open upper end or mouth with a chamber pedestal therein formed as an integral part thereof with each of the chambers in communication with the interior 25 of the receptacle.

A still further object of the invention is to provide an umbrella holder as a unitary article of manufacture consisting of a receptacle having an open upper end, an integral pedestal provided with umbrella receiving chambers, the lower ends of which are in communication with the interior of the receptacle, said pedestal further having a central bore for the reception of a standard 35 which may be utilized as a holder or handle or for other purposes according to the size, shape or configuration of said standard.

The bottom wall or base of the device has a hole in the region of the bore for the reception of a fastening device and the passageway of an electric cord if the same is used which cord may be also passed out through a hole in the rim of the device.

With these ends in view, this invention consists in the details of construction and combi-

nation of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is a perspective view of an umbrella holder constructed in accordance with my invention.

Fig. 2 is an enlarged plan view of one form of the umbrella holder without the standard.

Fig. 3 is a section on the line 3—3 of Fig. 2.

Fig. 4 is a fragmentary sectional view similar to Fig. 3 of another form of my invention embodying the preferred structural details.

In carrying out my invention as herein embodied, 5 represents a receptacle including a bottom wall 6 and generally upwardly projecting side walls 7 of any suitable or desirable contour or configuration but preferably so arranged as to provide a wide open upper end or mouth for a purpose which will be obvious from the following description. The bottom of the receptacle may be also formed or fashioned to provide a base rim 8 which acts as a support for the holder and in this rim may be formed a holder 9 for a purpose to be presently described.

Within the receptacle is located the pedestal 10 so fashioned or formed as to be an integral part of the complete holder when the latter is finished. Where the device is made of vitreous or similar materials, the receptacle is fashioned separately from the pedestal and the latter then joined to the receptacle prior to burning.

The pedestal has a plurality of umbrella tip receiving chambers 11 formed therein and the lower ends of said chambers are preferably in a higher plane than the bottom of the interior of the receptacle, as shown in Fig. 4 although the lower ends of said receptacles may be substantially at the same elevation as the interior of the bottom of the receptacle or even below the inner surface of the bottom of said receptacle, as shown in Fig. 3, but in any case, the bottom portion

or lower end of each chamber is in communication with the interior of the receptacle through an aperture 12 so that any drip water entering the chambers will flow 5 into the receptacle and may be readily removed from the latter by tilting the umbrella holder or by placing an absorbent article such as a sponge or piece of cloth in the receptacle through the upper open end or 10 mouth and then removing the absorbent article and squeezing or ringing the water therefrom as is well known. It is to be particularly noted that the construction herein set forth enables a person to remove the drip water without tilting or moving the umbrella holder.

In the pedestal is also formed a bore 13 which is preferably centrally located relative to the pedestal, particularly where the latter is of circular form as herein illustrated and in the bottom wall 6 of the receptacle in the region of said bore 13 so as to communicate with the latter is formed a hole 14 thereby permitting the insertion of a fastening device for engagement with the standard 15 when the latter is socketed in the bore 13 and said hole 14 may also be used for the passage of an electric conductor or cord which may also pass out through the hole 9 for attachment to an outlet or socket connected with a source of electrical energy.

Where the lower ends of the chambers 11 are above the inner surface of the bottom of the receptacle, channels 16 are formed in the bottom of the receptacle and blend into the very lowest part thereof as plainly illustrated in Fig. 4, therefore so long as a small amount of drip water enters the chambers, it will run out into the receptacle, but should the holder be unemptied for a considerable length of time so that a great amount of drip water accumulates, such drip water will rise in the chambers to the same extent as it rises in the receptacle although as said drip water is removed from the receptacle, any of the water in the chamber will flow into said receptacle.

Of course I do not wish to be limited to the exact details of construction as herein shown, as these may be varied within the limits of the appended claims without departing from the spirit of my invention.

Having thus fully described my invention, what I claim as new and useful is:—

1. As an article of manufacture, an umbrella holder comprising a receptacle having an open upper end, a base rim on said receptacle having a hole therethrough, a pedestal formed as an integral part of the receptacle and located within the same and having a plurality of chambers to receive the tips of umbrellas, said chambers being in communication with the interior of the receptacle through apertures formed in the pedestal in the region of the chambers, said

pedestal further having a bore and the bottom of the receptacle having an opening communicating with said bore and a standard socketed in the bore.

2. An umbrella holder comprising a receptacle including a bottom wall, and a pedestal formed integral with the said bottom wall of the receptacle to produce a unitary structure, said pedestal being centrally located within the receptacle, said pedestal having a plurality of substantially vertical chambers, the lower ends of which are in communication with the interior of the receptacle through horizontal openings leading from the sides of the lower ends of said chambers.

3. An umbrella holder including an upper open ended receptacle, and a chambered pedestal within said receptacle, the lower end of each chamber being above the inner surface of the bottom of the receptacle and in communication with the latter through side apertures and said inner surface of the bottom of the receptacle being channelled radially from each aperture to drain water from the lower ends of the chambers.

In testimony whereof, I have hereunto affixed my signature.

HERMAN R. KUEHNER.
